UNITED STATES PATENT OFFICE.

JOHN WILLIAM CRADDOCK, OF NEW YORK, N. Y.

DEVICE FOR THREADING PIPE.

SPECIFICATION forming part of Letters Patent No. 579,222, dated March 23, 1897.

Application filed March 25, 1896. Serial No. 584,763. (No model.)

To all whom it may concern:

Be it known that I, JOHN WILLIAM CRADDOCK, a citizen of the United States, and a resident of New York, in the county of New York and State of New York, have invented certain new and useful Improvements in Devices for Threading Pipes, of which the following is a specification, reference being had to the accompanying drawings, forming a part thereof, in which similar letters of reference indicate corresponding parts.

This invention relates to machines for cutting screw-threads on pipes, rods, and similar articles, and the object thereof is to provide an improved machine of this class which is simple in construction and operation and whereby a thread may be quickly and easily cut on a pipe or rod.

The invention is fully disclosed in the following specification, of which the accompanying drawings form a part, in which—

Figure 1 is an end view of my improved machine, and Fig. 2 a side view thereof, parts of the construction being shown in section.

In the drawings forming part of this specification, A represents a table, frame, or other support, and mounted thereon is a vise or clamp B, having a central transverse circular opening or passage b, through which a pipe, rod, or bar D is adapted to be passed, and mounted in the upper portion of the vise B is a vertically-movable screw-threaded rod D, which carries at its lower end a jaw d, which is preferably circular or segmental in form, and the upper end of the rod D is provided with a ring d².

Rigidly secured to one side of the table A is a bracket G, having vertical projecting side plates g, and mounted thereon is an arm H, which is provided at its upper end with a tubular head h, one end of which is screw-threaded, as shown by h², and the arm H is held in the bracket G by a cross-bar g³, which passes through the vertical projecting sides g at about the middle thereof, the said cross-bar g³ being triangular in cross-section and being connected with said vertical side plates by a tongue - and - groove construction, as clearly shown in Fig. 2.

Rigidly secured to the lower end of the arm G is an arm K, which projects at right angles thereto and which is provided at its outer

end with a vertical arm k, which is provided at its upper end with a ring-head k², through which passes a tubular sleeve M, the inner end of which is enlarged and screw-threaded, as shown at m, and on which is rigidly mounted a gear-wheel O, and detachably connected with the outer end of the tubular sleeve M is a die m², by which the thread is cut on the pipe or rod D in the operation of the machine, as hereinafter described.

Passing transversely through the vertical arm k, the arm H, and into the back of the bracket G is a shaft P, which is provided at its outer end with a crank R and on the central portion of which is mounted a gear-wheel S, which is adapted to operate in connection with the gear-wheel O on the tubular sleeve M.

The gear-wheel S is much longer than the gear-wheel O, or, rather, said gear-wheel S is much longer than the gear-wheel O is thick, and by reason of this fact the tubular sleeve M is free to move longitudinally without disconnecting the gear-wheel O from the gear-wheel S, and the operation will be readily understood from the foregoing description when taken in connection with the accompanying drawings and the following statement thereof.

The tubular head h is provided with an annular flange or rim h³, with which the arm H is connected with the ring-head k² of the arm k, and is provided with outwardly-directed arms k³, which serve as means for handling the same when detached from the bracket or for any desired purpose in operating the machine.

When it is desired to form a thread on a pipe, rod, or other article, the same is inserted through the vise B and passed through the tubular head h and through the tubular sleeve M. The die m², which may be of any desired form and which is provided with inwardly-directed cutting-points m³, is then connected with the end of the sleeve M, and the machine is operated by turning the crank R. The shaft P is turned by the crank R, and with it the gear S, which turns the gear-wheel O and the sleeve M, and as the sleeve M is turned it moves inwardly over the screw-threaded end of the tubular head h, and in this operation the required thread is formed on the end of the pipe or rod D.

Any desired number of dies m² may be em-

ployed, and one may be substituted for another whenever desired, and by reason of this fact a thread of any desired pitch or character may be made, and, as will be apparent, this device is simple in construction and operation and perfectly adapted to accomplish the result for which it is intended, and my invention is not limited to the size, form, and exact construction and arrangement of the parts herein described, and I reserve the right to make all such alterations therein and modifications thereof as fairly come within the scope of the invention.

Having fully described my invention, I claim as new and desire to secure by Letters Patent—

In a screw-threading device of the character described, the combination of a supporting-frame, a vise connected therewith, a bracket secured to said frame, an arm mounted in said bracket having a screw-threaded tubular head, a horizontal arm connected with

the lower end of the first arm, a vertical extension of said horizontal arm provided with a head or ring, a sleeve in said head or ring having an enlarged interiorly-screw-threaded part to receive the screw-threaded part of the tubular head, a gear-wheel on the tubular sleeve, a transverse shaft mounted in the first-named arm and in the vertical extension of the horizontal arm, a gear-wheel on said shaft, a crank to turn said shaft, and a die on the outer end of the tubular sleeve, all constructed and adapted to operate in the manner set forth.

In testimony that I claim the foregoing as my invention, I have signed my name, in presence of the subscribing witnesses, this 23d day of March, 1896.

JOHN WILLIAM CRADDOCK.
